Primary Examiner—Alan P. Douglas

Assistant Examiner—Lavone D. Tabor

(74) Attorney, Agent, or Firm: Harry I. Leon

() Term: 14 Years

(57) CLAIM

The ornamental design for a combined brush wiper and holder for paint can, as shown and described.

DESCRIPTION

FIG. 1 is a top, front, and left side perspective view of a combined brush wiper and holder for paint can showing my new design, the broken lines showing a paint can and paint brush being for illustrative purposes only and forming no part of the claimed design;

FIG. 2 is a bottom and right side perspective view thereof;

FIG. 3 is a cross-sectional view taken along line 3—3 of FIG. 1; and,

FIG. 4 is rear elevational view thereof.
